UNITED STATES PATENT OFFICE

JOHN H. BURKHOLDER, OF ASHLAND, OHIO, ASSIGNOR, BY MESNE ASSIGNMENTS, TO
ELITE MANUFACTURING COMPANY, A CORPORATION OF OHIO

SCAFFOLD BRACKET

Application filed April 19, 1928. Serial No. 271,134.

My invention relates to scaffold brackets, and in general the object of the invention is to provide a simple and durable bracket which may be readily attached to the walls or studding of a building and used as a part of a scaffold during the construction or repair of the building. To promote that purpose the bracket includes means which permits a hook connection to be made with a stud or upright scantling of the building, with the bracket located at either one side or the other of the stud or scantling, and this connecting device is also a foldable part of the bracket to permit same to be turned either horizontally or vertically to meet different conditions and permit different kinds of connections to be made, all as hereinafter shown and described and more concisely set forth in the claims.

20 In the accompanying drawings, Fig. 1 is a plan or top view on a reduced scale of two brackets as spaced apart and hooked to two studs as in use, and Fig. 2 is a side view of a bracket as hooked and attached. Fig. 3 is a side view, showing the foldable connecting part of the bracket turned vertically in flat bracing connection with the building wall. Fig. 4 is a perspective view of the bracket, partly folded. Fig. 5 is a detail perspective view of the upper scaffold engaging means.

The invention comprises a main bar or horizontal member 2 of angle iron, and a main brace member 4 of angle iron pivotally secured by a bolt or rivet 5 to the front end of bar 2. Bar 2 is designed to support one or more scaffold planks, and the outer end 6 thereof is turned upwardly to prevent displacement of the planks. The unfolding of 25 brace member 4 to an inclined bracing position in respect to bar 2 is limited by a pair of foldable connecting links 7 and 8, respectively. The lower end of brace member 4 is provided with a cross piece 9 of angle iron which is rigidly secured at right angles thereto by short braces 12. The length of cross piece 9 is sufficient to hold the bracket from swaying when suspended upon and against a wall or sheathing 10 of a building, or when 30 connected to a pair of upright studs or scant-

lings 11 forming part of the wall or building.

The means for connecting and suspending the bracket consists of a short section 14 of angle iron pivotally secured at its middle to the inner end of bar 2 by a bolt or rivet 15. 55 One flange 16 of section 14 is adapted to rest flat against the sheathing 10 when the section is turned at right angles to horizontal bar 2, and a series of key openings 17 therein permits the bracket to be suspended at different elevations upon one or more nails 18 driven into the sheathing or other part of the wall see Fig. 3. However, in erecting a wooden building the studding is uncovered to begin with and the bracket must then be 60 connected directly to the studs or uprights 11. These studs are spaced apart varying distances, and frequently single ones are flanged closely by other studs or pieces. Having this condition in mind a suitable connection element 19 is mounted in a transversely shiftable or reversible position upon one end of foldable section 14 to permit the sections to be attached at either side to a stud. 70

As shown, element 19 is in the form of a 75 double hook, that is, it has a hook at each end, and it is supported to slide within fixed limits in one flange of section 14 and in a supplemental angle piece 20 welded to flange 16, see Fig. 5. Accordingly, when foldable section 14 is turned parallel with bar 2 flange 16 engages and rests upon the top thereof, as seen in Fig. 2. Section 14 then serves as an extension of bar 2 whereby the connecting element or hook 19 may be placed rearwardly of the stud and in a position where it can hook around or embrace it, as seen in Fig. 1. Moreover, a hook connection can be made with the stud from either side of the stud, that is, when the bracket is placed either to the left or to the right of the stud, inasmuch as the hook is reversible or movable to the left or right of bar 2. In the present device, I use a reversible hook which slides within a foldable extension for the main bar of the bracket, but in considering the invention more broadly I desire to include any equivalent connecting means which will permit the bracket to be affixed to either the front of a wall or to the studding and which will also 80 85 90 95 100

permit the bracket to be placed on either the right or left side of the studding in making the connection.

What I claim, is:

- 5 1. A scaffold bracket comprising a main bar, a brace member for said bar, an extension pivotally connected to said main bar, said extension being provided with nail openings and a hook member supported by one 10 end of said extension for alternative connection of said extension in vertical or horizontal position to different portions of a building wall.
- 15 2. A scaffold bracket comprising a main bar and a brace member, including a pivoted supporting section at one end of said bar having a member shiftably attached to one end thereof, said shiftable member being of U-shaped form and attached with its central 20 portion to said supporting section.
- 25 3. A scaffold bracket including a main bar having a perforated section pivoted to one end thereof, and a member of U-shaped form shiftably connected with its central portion 25 to said section.
- 30 4. A scaffold bracket including a main bar, an extension pivotally connected to one end of said bar and attachment means for said extension, said means including a member 35 slidably mounted within said extension and in a plane at right angles to the longitudinal axis of the extension.
- 35 5. A scaffold bracket including a main bar, a brace member pivotally connected with one end of said bar, and a U-shaped member slidably connected at its central portion to the opposite end of said bar.
- 40 6. A scaffold bracket comprising a horizontal bar of angle iron, a perforated extension of angle iron pivotally connected to said bar, a member having projections at right angles to its ends carried by said extension and shiftable to opposite sides thereof, and foldable braces for said bar.
- 45 7. A scaffold bracket comprising a horizontal bar, a brace member pivotally connected at one end to said bar and having a stabilizing cross member at its opposite end, means for limiting the spread of said brace member, a perforated section at one end of said bar adapted to be folded thereon and a U-shaped member carried by said section and shiftable to opposite sides thereof.
- 55 8. A scaffold bracket including a horizontal bar, an inclined brace member pivoted to said bar having a cross piece at one end, an extension pivotally connected to said bar adapted to be folded thereon, and a slidably shiftable member at one end of said extension, said extension having means wherein the second member may be slid and shifted.

In testimony whereof I affix my signature.
JOHN H. BURKHOLDER.
